UNITED STATES PATENT OFFICE

2,616,606

RECEPTACLE FILLING MACHINE

Paul C. Beehler, Jr., Lewiston, N. Y., assignor to
Chisholm-Ryder Company, Incorporated, Niag-
ara Falls, N. Y., a corporation of New York

Application January 14, 1950, Serial No. 138,583

2 Claims. (Cl. 226—97)

1

This invention relates to a receptacle filling machine, and more particularly to such a machine which will operate at a high rate of speed and at the same time uniformly fill receptacles with accurate amounts of solid or liquid materials, or both.

The present invention is more particularly directed to an improvement on the type of filling machine described in the Ayars Patent 2,279,651 dated April 14, 1942, for Receptacle Filling Machine, and in common with this Ayars machine functions to provide increased capacity by first depositing in each can or receptacle a substantial amount of liquid, then dropping the discrete or solid materials into the can, and finally filling the can or receptacle with the additional liquid required to provide the desired total liquid content of the can.

A specific object of the present invention is to provide, for both the initial and the final liquid filling, an increased time interval for the flow of liquid into the receptacle thereby to permit of a higher capacity of the machine, the capacity of the machine being determined by the rate of liquid fill, particularly by the time required for the liquid to find its way and settle into the voids between the discrete solid materials.

Another object is to provide such increased liquid filling time intervals without costly alteration of the said Ayars machine.

Other objects and advantages of the invention will appear from the following description and drawings in which:

Fig. 1 is a side elevational view, partly in section, of a can filling machine embodying the present invention.

Fig. 2 is a vertical sectional view taken generally on line 2—2, Fig. 1.

Fig. 3 is a top plan view, partly in section.

Fig. 4 is a vertical sectional view taken on line 4—4, Fig. 3.

Fig. 5 is an enlarged horizontal sectional view taken on line 5—5, Fig. 2.

Fig. 6 is an enlarged sectional view taken on line 6—6, Fig. 4.

The principal operating parts of the can filling machine are carried by a table-like supporting casting 10 having a central upwardly projecting hub 11 having an integral, depending bearing sleeve 12 in which a tubular or hollow vertical shaft 13 is journalled by means of bearing bushings 14. The table-like supporting casting 10 has a depending marginal skirt 15 supported on the upper rim 16 of a supporting bed 18, the generally rectangular side walls 19 of which are supported on the floor and one of which side walls can be provided with an access opening 20.

One of these side walls 19 of the supporting

2

bed 18 carries a bearing bracket 21 having a pair of bearing bushings 22 for a horizontal drive shaft 23 which projects outwardly from the bed 18 and at its inner end has fast thereto a bevel pinion 24 meshing with a bevel gear 25 fast to the lower end of the hollow or tubular shaft 13.

The hollow or tubular shaft 13 extends up through the bearing bushings 14 and has a star wheel 26 keyed thereto while the extreme upper end of this tubular or hollow shaft 13 has keyed thereto a funnel casting indicated generally at 28. A solid shaft 29 extends vertically through the hollow shaft 13 and into the sunken central chamber or downwardly recessed portion 31 (see Fig. 2) of the funnel casting 28 and this solid shaft 29 on its upper end has keyed thereto a pinion 32 which meshes with a gear 33 fast to a shaft 34. This shaft 34 is journalled in a depending bearing sleeve 36 formed integrally with a stationary plate 37. This shaft 34 also passes upwardly through a collar 38 integral with and rising from a lower turret member 39. The shaft 34 is fastened to the collar 38 by means of a set screw 40. The lower turret member 39 is provided with an annular series of upstanding sleeves or ring flanges 41 which are arranged in a circle about the axis of the shaft 34. An upper turret member 42 is provided with an annular series of depending sleeves or ring flanges 43 which are complementary to and fit into the upstanding ring flanges 41 of the lower turret member 39 so as to form adjustable telescopic measuring cups.

The upper turret member 42 is provided, in axial alignment with the stub shaft 34, with an integral upstanding pin or lug 44 on which is keyed a pinion 46, this pinion meshing with a ring gear 47 on the inside of the bottom or base 48 of a hopper 49. This bottom or base 48 of the hopper is also extended over the top of the entire upper turret member 42 so as to form a cover therefor.

The bottom of the lower turret member 39 fits on a wear plate 50 within a recess 51 on the upper face of the stationary plate 37, and its center of rotation is the axis of the stub shaft 34, while the center of rotation of the funnel casting 28 is the axis of the vertical solid and hollow shafts 29 and 13.

At one side of the hopper 49, and located near the periphery of the stationary plate 37 is an upright cylindrical stud 52 fixed to this stationary plate and which is provided with a threaded bore 53. This stud 52 is embraced by a vertically movable adjusting sleeve 54 having a laterally extending arm 55 supporting the rim of the upper turret member 42. An adjusting screw 56 having a hand wheel 58 is screwed into the threaded

bore 53, this adjusting screw having an enlargement 59 engaging an annular shoulder 60 at the upper end of the adjusting sleeve 54. It will be seen that upon turning the hand wheel 58 to screw it upwardly in the threaded bore 53, its enlargement 59 will raise the adjusting sleeve 54 and its laterally extending arm 55. This will in turn raise the upper turret member 42 so as to move its telescopic sleeves 43 upwardly and thereby increase the size of the measuring cups provided by these sleeves with the companion telescopic sleeve 41 of the lower turret member 39.

The funnel casting 28 is provided with an annular series of depending material directing pockets or funnels indicated generally at 61, these funnels being arranged concentric with the axis of the concentric hollow and solid shafts 13 and 29 and terminating in a reduced lower neck 62 through which the solid and liquid materials supplied to the upper ends of these funnels are discharged. Each of these funnels 61 is provided with an inclined internal partition 63 which is concentric with the axis of the concentric hollow and solid shafts 13 and 29 and divides the funnel into an inner generally semicircular pocket or chute 64 for the solid materials and an outer arcuate pocket or chute 65 for liquid. Each partition 63 terminates short of the bottom of its funnel 61 and both the solid materials introduced through the inner semicircular pockets or chutes 64 and the liquid introduced through the outer arcuate pockets or chutes 65 flow out through the reduced lower necks 62 of the funnels. It will particularly be noted that the outer arcuate pockets or chutes 65 present arcuate inlet openings 66 which are concentric with the axis of the concentric hollow and solid shafts 13 and 29. A part of the length of each of these arcuate openings 66 can be cut off by a horizontal web 68 across the corresponding ends of these inlet openings.

The stationary plate 37 is provided with an elongated arcuate discharge opening 70 located as shown in Fig. 3 and shown in Fig. 1 as arranged over one of the solid materials pockets or chutes 64. To effect the transfer of the solid materials from the hopper 49 through this discharge opening 70 to the solid materials pockets or chutes 64, the vertical solid shaft has a bevel gear 71 fast to its lower end and this gear meshes, as best shown in Fig. 4, with a pair of bevel pinions 72 each fast to the lower end of an inclined shaft 73 suitably journaled in stationary bearing bushings 74, 75 and 76 and 78.

The bearing bushing 74 is in a bearing bracket 79 supported by an arm 80 from a bearing housing 81 which is in turn supported by an arm 82 from the rim 16 of the bed 18. This bearing housing 81 carries bearing bushings 83 and 84 for the hollow shaft 13 and the solid shaft 29, respectively. The hollow shaft 13 is supported by a thrust bearing 85 interposed between the star wheel 26 and the stationary table-like supporting casting 10, and the solid shaft 29 is shown as supported by a thrust bearing 86 interposed between the pinion 32 and the top of the hollow shaft 13. The bearing bushing 75 for each inclined shaft 73 is carried by a housing 88 suitably supported in the apron 15 of the table-like supporting casting 10. Each pair of bearing bushings 76 and 78 is arranged in the axially aligned sleeves 89 and 90 which are formed integrally with and project upwardly and downwardly, respectively, from the circular inclined bottom 91 of a liquid container indicated generally at 92.

Each of the liquid receptacles 92 is supported by a bracket 93 integral with its bottom plate 91 and suitably secured to the rim of the stationary plate 37.

Fast to each of the inclined shafts 73 is a star wheel 94 the arms 95 of which are engaged by rollers 96 mounted on depending pins 98 on the arms of the star wheel 26. This last star wheel 26 is fixed to the hollow vertical shaft 13 and since this shaft is continuously driven it will be seen that the rotation of the star wheel 26 on the hollow vertical shaft 13, through the rollers 96, imparts a step-by-step rotation to each of the star wheels 94 and inclined shafts 73, this being transmitted through the gears 72 and 71 to the solid vertical shaft 29.

This intermittent rotation of the solid vertical shaft 29 is imparted to the upper and lower turret members 42 and 39 so as to bring the telescopic measuring cups 43 and 41 thereof progressively under the hopper 49 and over the arcuate opening 70 of the stationary plate 37. Accordingly, these telescopic measuring cups 43, 41 withdraw measured quantities of solid materials from the hopper 49 and discharge the same through the arcuate opening 70 of the stationary plate 37 into the solid materials pockets or chutes 64 of the funnel casting 28 which is also fast to and rotating with the vertical hollow shaft 13. At the same time the pinion 48 fast to the upper face of the upper turret member 42 meshing with the ring gear 47 on the base 48 of the hopper 49, causes rotation of this hopper 49 to facilitate filling of the telescopic measuring cups 43, 41.

Each of the liquid receptacles 92 has a side wall 100 rising from the rim of the bottom plate 91 of the receptacle coaxial with the corresponding inclined shaft 73, the top rim of each of these side walls being preferably horizontally disposed. Within each liquid receptacle 92 is arranged a turret member indicated generally at 101 and comprising a central sleeve 102 rotatably fitting the sleeve 90 of the receptacle 92, a plurality of arms 103 radiating from this central sleeve 102 and rim 104 fitting the bottom plate 91 of the receptacle and carrying an annular series of liquid measuring cups or sleeves 105 which are open at their tops and bottoms, as best shown in Fig. 4, and are arranged to travel into and out of register with a discharge opening 106 in the bottom plate 91 of the liquid receptacle. The liquid is discharged from each of the liquid measuring cups or sleeves 105 of the turret 101 into the open upper end of a neck 108 integral with and rising from the stationary plate 37. It will particularly be noted that the measuring cups 105 are of elongated arcuate form concentric with their axis of rotation and preferably of approximately the same arcuate length as the arcuate length of the arcuate liquid pockets or chutes 65 of the funnel casting 28. Also while each of the discharge openings 106 and the bore 109 through the corresponding neck 108 can be circular, it is important that each arcuate measuring cup 105 and a corresponding arcuate pocket or chute 65 of the funnel casting 28 be in register with the corresponding discharge opening 106 and bore 109 simultaneously for their full length so that liquid is discharged into the arcuate pockets or chutes 64 for the full length of travel of these arcuate pockets or chutes under each bore 109.

The bottom plate 91 of each of the liquid receptacles 92 inclines downwardly and outwardly from its discharge opening 106 and since the turret 101 is parallel with this bottom plate, its

measuring cups 105 travel from a lowered position diametrically opposite to the discharge opening 106 to an elevated position directly over this discharge opening. The level of the liquid 110 in each receptacle 92 is such as to be at or below the rim of the uppermost measuring cups 105 and above the rims of the other measuring cups.

The series of measuring cups 105 of each of the liquid receptacles 92 are adjustable as to capacity as a group, such adjustment determining the amount of preliminary and final liquid fill. For this purpose an arcuate plug 111 is arranged in each measuring cup 92 and is suspended from the rim of a spider 112 associated with each liquid receptacle. A pair of sliding pins 113 are fixed to the hub of each of these spiders 112, these pins projecting parallel with the corresponding inclined shaft 73 and slidably fitting the enlarged rim 114 of the central sleeve 102 of the turret 101. The plugs 111 thereby rotate in unison with the measuring cups 105 of the turret 101. An adjusting screw 115 has its enlarged threaded end screwed into a threaded end bore in the corresponding inclined shaft 73, the reduced end 116 of this screw extending through an axial bore in the spider 112 and having keyed thereto a handwheel 118. It will be seen that upon turning this handwheel 118 the screw 115 will be turned to raise or lower the spider 112 and hence adjust the degree of projection of the plugs 111 into the measuring cups 105 thereby to adjust the capacities thereof.

The upper end of each inclined shaft 73 can be squared to fit a squared opening in an end head 114 of the central sleeve 102 of the turret 101 so that this shaft rotates the turret.

The machine can be provided with any suitable type of mechanism for feeding cans 120 and since this can feeding mechanism forms no part of the present invention it is not illustrated in detail. The line of empty cans is received from a canway 121 (Fig. 3) on a shelf-like casting 122 secured to the apron 15 of the table-like supporting casting 10 at one side of the machine and having a slot 123 in alignment with the canway 121, the upper stretch of a can feed chain 124 riding in this slot. This feed chain (Fig. 2) passes around a pair of sprockets, the drive sprocket being shown at 125 as fast to a horizontal shaft 126 journaled in bearing blocks 128 secured to the underside of the shelf-like casting 122 and having a bevel pinion 129 at one end. This pinion 129 meshes with a bevel gear 130 on a vertical star wheel shaft 131 journaled in and projecting upwardly from the shelf-like casting 122. This vertical shaft 131 is driven from the continuously rotating vertical hollow shaft 13 through a gear 132 fast to this hollow vertical shaft and meshing with a pinion 133 fast to this vertical star wheel shaft 131.

The cans can be aligned on the feed chain 124 by a horizontal tapered screw 135 on the shelf-like casting 122 and rotated in any suitable manner (not shown) and the feed chain feeds the cans against a stationary circular guide rail 136 (Fig. 3) and to the teeth of a star wheel 138 fast to the upper end of the star wheel shaft 131. The star wheel 138 and guide rail 136 deliver the individual cans to platforms 140 (Fig. 2) at the ends of the arms of the star wheel 26, these platforms being in line with the discharge nozzle 62 of the funnels 61 of the funnel casting 28. The solid and liquid materials deposited in these funnels 61 is therefore deposited in the cans 120 arranged therebelow. It will be understood that

the usual means for elevating the platforms 140 during filling of the cans thereon and also that the usual no can-no fill mechanism would be provided, such forming no part of the present invention, however, and hence not being shown.

In the operation of the machine the hollow tubular shaft 13 (Fig. 2) is continuously rotated through its gear connection 25, 24 with the horizontal drive shaft 23. Accordingly, the parts fast to this hollow tubular shaft 13 are continuously rotated, this comprising the gear 132 which drives the can feeding mechanism; the star wheel 26 carrying the platforms 140 which receive cans from the can feeding mechanism; and the funnel casting 28 carrying the funnels 61 which separately receive the liquid and solid materials and which deposit the same into cans 120 positioned therebelow on the supporting platforms 140 of the star wheel 26.

As the star wheel 26 rotates its rollers 96 successively engage (Fig. 4) the teeth 95 of the star wheels 94, each of these star wheels being fast to a corresponding inclined shaft 73. Accordingly, a step-by-step movement is imparted to each of these inclined shafts 73 and this step-by-step movement is imparted to bevelled gears 72 at the lower ends of these shafts. These bevelled gears mesh with and turn the bevel gear 71 at the lower end of the solid vertical shaft 29.

The step-by-step rotation of the solid vertical shaft 29 (Fig. 1) rotates the gear 32 fast thereto, this in turn rotating the gear 33 fast to the stub shaft 34. This rotation of the stub shaft 34 rotates the lower turret member 39 and the rotation of this lower turret member 39, through the telescopic measuring cups or sleeves 41, 43 rotates the upper turret member 42. Accordingly, the turret members 39, 42 are rotated about the axis of the stub shaft 34 and the telescopic pockets 41, 43 thereof are progressively brought under the hopper 49 so as to be filled with the solid materials. These telescopic pockets 41, 43 travel under the bottom plate or base 43 of the hopper 49 and into register with the arcuate discharge opening 70 of the stationary plate 31, the solid materials being discharged by the measuring cups 41, 43 through this arcuate discharge opening 70 and being received in the inner pockets or chutes 64 of the funnels 61 carried by the funnel casting 28. These funnels 61 deliver the solid materials through their outlet necks 62 into the cans 120 positioned therebelow on the platforms 140 of the star wheel 26.

During operation the hopper 49 is rotated, this rotation being effected by the pinion 46 fast to and concentric with the rotating upper turret member 42 meshing with the ring gear 47 on the base 43 of the hopper.

The cans to be filled are received from a canway 60 121 (Fig. 3) on the shelf-like casting 122 and come into engagement with the upper stretch of a feed chain 124 projected through a slot 123 through this table-like casting. In moving along with the chain 124 the cans are properly positioned by the rotating taper screw 135 and are delivered to the star wheel 138 and carried by this star wheel and the circular guide rail 136 on the platforms 140 of the star wheel 26 (Fig. 2), these platforms, as previously described, being located to register with the discharge nozzles 62 of the funnels 61. The drive for this can feed mechanism is from the hollow vertical shaft 13 through the gears 132 and 133; vertical star wheel shaft 131 carrying the star wheel 133; and

through the pinions 130 and 129 to the drive sprocket 125 for the chain 124.

The present invention relates to improvements in the feed of liquid from the two liquid receptacles 92 into outer arcuate pockets or chutes 65 of the funnels 61. The liquid is delivered in successive amounts from the two liquid receptacles 92, the feed of liquid from one of these receptacles being arranged in advance of the solid materials discharged through the discharge opening 70 and the feed of liquid from the other of these receptacles being arranged on the opposite side of this solid materials discharge opening 70 so that the cans 120 are first filled with a predetermined amount of liquid, then filled with the solid materials, and thereafter filled with the final amount of liquid, such successive fillings having been found to provide increased time for the percolation of the liquid through the voids among the solid materials.

In each of the liquid receptacles 92 a body of liquid is maintained at the level indicated and as the turret 101 rotates with its angular shaft 73 its pockets 105 are filled with liquid on the lower side of the turret, the degree of fill being determined by the degree of penetration of the plugs 111 as adjusted by turning the hand wheel 118 and adjusting the screw 115. As each measuring pocket passes through its maximum elevation, it comes into register with the liquid discharge opening (Fig. 4) and its contents flow through this opening and through the bore 109 of the sleeve 108 into the arcuate liquid pocket or chute 65 then in register therewith.

It will be particularly noted that the pockets 105 of the turret 101 are of elongated arcuate form and that the length of these pockets is substantially equal to the effective arcuate length of the liquid pockets or chutes 65 of the funnel casting 28. This effective length of the pockets 65 is determined by the horizontal webs 68 at the ends of these pockets. These turrets 101 and the funnel casting 28 are also synchronized so that each measuring pocket 105 of each turret 101 comes into communication with the bore 109 of the discharge neck 108 at the same time that a corresponding liquid pocket or chute 65 of the funnel casting 28 comes into communication with this bore 109 of the sleeve 108. Since these measuring pockets of the turret and liquid chutes of the funnel casting are of the same effective length it will be seen that each companion pair are in communication with each other for their full length of travel past each other even though the opening connecting them is of round form. Accordingly, by this arrangement a maximum time of communication is provided between the measuring pockets 105 of the turret 101 and the liquid chutes or pockets 65 of the funnel casting 28 and hence the capacity of the machine is increased since this capacity is determined by the length of time required for the flow of liquid into the cans and not by the filling of the cans with the solid materials.

The successive charges of liquid so introduced into the pockets or chutes 65 of the funnel casting 28, of course, flow through the outlet spouts 62 thereof into the cans positioned therebelow.

From the foregoing it will be seen that by the arcuate form of the liquid measuring pocket 65 an increased time is provided for the emptying of each of these pockets into the arcuate chutes or pockets 65 of the funnel casting 28 and also into the cans thereby to provide a machine of increased capacity as compared with that shown in the Ayars patent above referred to.

I claim:

1. In a receptacle filler having a funnel member arranged to rotate about a generally vertical axis and having an annular series of substantially equally spaced funnels arranged to discharge into a progression of cans arranged therebelow and each of said funnels forming a chute of horizontally elongated arcuate form concentric with said axis, said chutes being of substantially equal arcuate length, the combination therewith of means for feeding predetermined amounts of liquid through said chutes into said cans, comprising a turret arranged to rotate about a generally vertical axis arranged outside of said funnel member, an annular series of substantially equally spaced horizontally elongated arcuate open bottom measuring pockets of substantially equal arcuate length carried by said turret and arranged concentric with said turret axis and arranged to travel, at one side of said turret, above and in close proximity to the line of travel of said arcuate chutes, a stationary plate closing the bottoms of said measuring pockets, and means arranged to fill said measuring pockets with liquid, said stationary plate being provided with a discharge opening arranged to establish communication between said measuring pockets and chutes as said funnel member and turret are rotated.

2. In a receptacle filler having a funnel member arranged to rotate about a generally vertical axis and having an annular series of substantially equally spaced funnels arranged to discharge into a progression of cans arranged therebelow and each of said funnels having a partition generally concentric with said axis and forming an outer chute of horizontally elongated arcuate form concentric with said axis and said chutes being of substantially equal arcuate length, the combination therewith of means for feeding predetermined amounts of liquid through said chutes into said cans, comprising a turret arranged to rotate about a generally vertical axis arranged outside of said funnel member, an annular series of substantially equally spaced horizontally elongated arcuate open bottom measuring pockets of substantially equal arcuate length carried by said turret and arranged concentric with said turret axis and arranged to travel, at one side of the turret, above and in close proximity to the line of travel of said arcuate chutes, a stationary plate closing the bottoms of said measuring pockets, means arranged to fill said measuring pockets with liquid, said stationary plate being provided with a discharge opening simultaneously in communication with each of said arcuate chutes and a companion measuring cup, and means driving said funnel member and turret at speeds to render said communication substantially contemporaneous during the entire travel of each of said measuring pockets over said discharge opening.
